US00D779215S

(12) **United States Design Patent** (10) Patent No.: **US D779,215 S**
(45) Date of Patent: **** Feb. 21, 2017**

(54) **SUBSTRATE WITH CAMOUFLAGE PATTERN**

(71) Applicant: **Dschulnigg GmbH & Co KG**, Lamprechtshausen (AT)

(72) Inventor: **Thomas John Brencick**, Kleinostheim (DE)

(73) Assignee: **Dschulnigg GmbH & Co KG**, Lamprechtshausen (AT)

(**) Term: **15 Years**

(21) Appl. No.: **29/532,296**

(22) Filed: **Jul. 4, 2015**

Related U.S. Application Data

(60) Division of application No. 29/477,383, filed on Dec. 20, 2013, now Pat. No. Des. 736,000, which is a continuation-in-part of application No. 29/450,821, filed on Mar. 22, 2013, now Pat. No. Des. 729,524.

(57) **CLAIM**

I claim the ornamental design for a substrate with camouflage pattern, as shown and described.

DESCRIPTION

The patent or application file contains at least one drawing executed in color. Copies of this patent or patent application publication with color drawing(s) will be provided by the office upon request and payment of the necessary fee.

The sole FIGURE is a plan view of a substrate with camouflage pattern showing my new design.

**1 Claim, 1 Drawing Sheet
(1 of 1 Drawing Sheet(s) Filed in Color)**
